The ornamental design for a remote control vehicle chassis adapter, as shown and described.

DESCRIPTION

FIG. 1 is an isometric view of a first embodiment of a remote control vehicle chassis adapter.

FIG. 2 is a top view of the remote control vehicle chassis adapter of FIG. 1.

FIG. 3 is a bottom view of the remote control vehicle chassis adapter of FIG. 1.

FIG. 4 is a front view of the remote control vehicle chassis adapter of FIG. 1.

FIG. 5 is a rear view of the remote control vehicle chassis adapter of FIG. 1.

FIG. 6 is a left view of the remote control vehicle chassis adapter of FIG. 1.

FIG. 7 is a right view of the remote control vehicle chassis adapter of FIG. 1.

FIG. 8 is an isometric view of a second embodiment of a remote control vehicle chassis adapter.

FIG. 9 is a top view of the remote control vehicle chassis adapter of FIG. 8.

FIG. 10 is a bottom view of the remote control vehicle chassis adapter of FIG. 8.

FIG. 11 is a front view of the remote control vehicle chassis adapter of FIG. 8.

FIG. 12 is a rear view of the remote control vehicle chassis adapter of FIG. 8.

FIG. 13 is a left view of the remote control vehicle chassis adapter of FIG. 8.

FIG. 14 is a right view of the remote control vehicle chassis adapter of FIG. 8.

FIG. 15 is an isometric view of a third embodiment of a remote control vehicle chassis adapter.

FIG. 16 is a top view of the remote control vehicle chassis adapter of FIG. 15.

FIG. 17 is a bottom view of the remote control vehicle chassis adapter of FIG. 15.

(Continued)

FIG. **18** is a front view of the remote control vehicle chassis adapter of FIG. **15**.

FIG. **19** is a rear view of the remote control vehicle chassis adapter of FIG. **15**.

FIG. **20** is a left view of the remote control vehicle chassis adapter of FIG. **15**; and,

FIG. **21** is a right view of the remote control vehicle chassis adapter of FIG. **15**.

The broken lines and the areas within them in FIGS. **15**, **16**, **17**, **18**, **19**, **20**, and **21** depict portions of the remote control vehicle chassis adapter that form no part of the claimed design.
